SPARK PLUG

Earl M. Hall, Salem, Oreg., assignor of one-half
to Henry Carl, Salem, Oreg.

Application June 18, 1940, Serial No. 341,193

2 Claims. (Cl. 123—169)

This invention relates to improvements in spark plugs and the primary object of the invention is to design a plug that will not foul or become short circuited.

Another object of the invention is the provision within the plug for air cooling the same by air circulation.

These and other incidental objects will be apparent in the drawing, specification and claims to follow.

Referring to the drawing:

Figure 1 is a side elevation of my new and improved spark plug.

Figure 2 is a sectional view of the plug, parts broken away for convenience of illustration.

Figure 3 is a plan sectional view, taken on line 3—3 of Figure 2.

Figure 4 is another preferred form of embodiment of my new and improved spark plug.

Figure 5 is a plan view of Figure 4.

In the drawing:

1 is the main body portion of the spark plug, having the usual threaded extensions 2 for entering the motor block. The usual central electrode 3 is encased within the porcelain or insulating material 4 of usual construction. The lower end 2 of the plug is cored out at 5, slightly larger than the lower end 6 of the insulator 4. The lower end of the core 5 is partially closed by the bottom 7 of the lower part of the plug 2. A cup-like insulator gasket 8 rests on the bottom 7 and receives the lower portion of the insulator 6, best shown in Figure 2. The end 7 has an opening 9 larger than the lower end 10 of the electrode 3. This is where the spark gap is provided.

It will be noted that the opening 9 is very shallow, leaving no place for dirt to lodge. The power of the explosion will clean this spark gap chamber from any foreign matter. It will be noted that the end 7 of the lower part 2 of the spark plug is rounded in the shape of a semi-circle. The reason for this construction is to provide self-cleaning of the end of the plug by the power of explosion within the cylinder head. This is a very important feature of my new and improved spark plug.

In the construction of the lower part of the porcelain 6, the gasket 8 seals all of the space between the porcelain and the lower body of the plug 2 so that there is no space for dirt or carbon to generate. This is another high-light of the invention, which is very important. The only space provided is the space 9 where the spark takes place and this space is so shallow that no

dirt can lodge without being forced out by combustion.

Another feature is the provision of ventilators 11 within the body of the plug 1 for allowing air to reach the insulator 4, spaced around its lower end 6 for cooling the same. There are a number of ventilator openings 11 provided for this purpose, terminating in the hollow chamber 12 which is connected to the space 5 surrounding

10 the lower terminal 6 of the insulator 4. The insulator 4 is held in place by the usual lock nut 13 and gasket 14.

The cup-like gasket 8 may be made of insulating material in which case the bottom part of 15 the gasket could extend over to the electrode 10 or the gaskets may be made of metallic material and extend to the edge of the openings 9, as shown in Figure 2. This material should expand to correspond with the rest of the plug so that a 20 tight fit may be maintained.

Referring to Figures 4 and 5, I illustrate another preferred form of insulator terminal mounting, where the lower end 16 of the insulating terminal is made relative short resting 25 within the insulating material 17. The shoulder 18 of the insulator is forced downward by the gasket 19 underneath the locking nut 20, which is threaded into the main body of the spark plug 15. In this construction the distance between the

30 locking gasket 19 and the lower end of the insulator terminal 16 is shortened; this is desirable when it comes to expansion by heat. The lower end of the locking nut 20 has openings or notches 21A leading to the vertical grooves 21.

35 This permits the circulation of air from openings 22 within the main body of the plug 15 where air is allowed to pass from the atmosphere through the openings 22 and openings 21A and up through the groove or flute 21 around the 40 main insulator terminal, cooling the whole assembly.

I do not wish to be limited to the particular mechanical construction illustrated and claimed, as other forms of mechanical embodiment may 45 be employed, still coming within the scope of the claims to follow.

What is claimed as new is:

1. A spark plug including a metallic body 50 formed with a threaded extension to secure the plug in place, the lower end of the extension being formed with an annular opening forming an electrode, the lower end of the body being upwardly curved from the edge of the opening, an insulating body having a part seated within the extension and spaced from an interior bore

thereof, the body being circumferentially enlarged above the parts fitted within the extension, a strip arranged between the extension of the insulating body and the wall of the bore the lower edge of the strip terminating in line with the edge of the opening and the upper edge of the strip terminating within the extension below the enlargement of the insulating body, said strip underlying and forming a support for the insulating body, an electrode extending longitudinally of the insulating body and terminating within and spaced from the wall of the opening in the lower end of the threaded extension of the me-

tallic body to thereby provide a spark gap, the insulating body above the extension of the metallic body being spaced from the latter to provide a ventilating chamber, the metallic body being formed with a plurality of radiating openings leading from the ventilating chamber through the metallic body for ventilation.

5 2. A construction as defined in claim 1 where-
in a strip between the conducting body and in-
10 sulating within the bore of the threaded exten-
sion is of insulating material.

EARL M. HALL.
